WILLIAM E. BECKER, OF CHICAGO, ILLINOIS, ASSIGNOR TO GOSS PRINTING PRESS COMPANY, A CORPORATION OF ILLINOIS

FOLDING ROLLER

Application filed October 23, 1929. Serial No. 401,684.

This invention relates to a novel and useful rotary folding mechanism and more especially to such a folding mechanism for use in connection with the folding of newspapers 5 which vary greatly in the number of pages.

Objects and advantages of the invention will be set forth in part hereinafter and in part will be obvious herefrom, or may be learned by practice with the invention, the same being realized and attained by means 10 of the instrumentalities and combinations pointed out in the appended claims.

The invention consists in the novel parts, construction, arrangements, combinations 15 and improvements herein shown and described.

The accompanying drawings, referred to herein and constituting a part hereof, illustrate one embodiment of the invention, and 20 together with the description, serve to explain the principles of the invention.

Of the drawings:

Figure 1 is an elevation of a folding mechanism constructed in accordance with the present invention, with certain parts broken away, and others shown in section.

Figure 2 is an elevation of the mechanism shown in Figure 1, looking from the other end of the folding cylinder, and showing the 25 driving means for the various folding rollers.

Figure 3 is a partial horizontal section taken on the line 3—3 of Figure 1.

Figure 4 is a detailed section taken on the line 4—4 of Figure 1, and

Figure 5 is an end view looking from the right of Figure 1.

The exemplary illustrated mechanism embodies mainly a rotary folding cylinder taking and carrying the sheet or group of sheets 40 constituting the newspaper or the like, and having mounted therein a rotatable tucking blade which is actuated at the proper time to medianly and transversely fold the sheet or groups of sheets into the bite of a pair of folding rollers, thereby folding and feeding off the sheets in the usual manner, together with novel improvements in said structure.

By the present invention, the folding rollers are simultaneously movable toward and 45 away from each other, and preferably toward

and away from the folding cylinder and line of fold of the folding blade with which the rollers cooperate as the sheet or group of sheets is tucked between the folding roller by means of the folding or tucker blade. 55

Preferably, the folding rollers are so moved that the distance between them and the folding cylinder is increased sufficiently as the folding rollers are moved away from each other to accommodate a larger number of 60

sheets, between the rollers and cylinders so that the head of the sheet or sheets to be folded will be allowed to pass the forward folding roller and there will be no tendency for the outside sheet to be combed off the folding cylinder by the folding rollers. The present invention also provides a folding mechanism capable of folding products of widely varying sizes and which dispenses with the necessity for adjusting the position of the 65

folding or tucker blade to vary the distance it projects from the folding cylinder or for substituting a blade of one width for a blade of another width, as has heretofore been necessary. 75

Preferably, and as embodied in the present illustrative embodiment of the invention, the folding rollers are always maintained in parallelism with each other and with the folding cylinder, and as preferably normally 80 maintained equidistant from the line of strike of the folding blade. Also, one of the folding rollers is preferably resiliently mounted at each of its ends and is movable toward and away from the other folding roller with which it cooperates, thereby providing the proper pinch for receiving the sheet or sheets by the fold, and also providing an automatic release for any small chokes of the folder. 85

The folding blade actuating means is preferably a rotary disc cam, having a plurality of cam slots therein adapted to cooperate in succession, that is, for successive folds, with the folding or tucking blade actuating mechanism, to make the successive folds, although the folding or tucker blade may be actuated by any other suitable means. 90

Other features of the invention will be initially pointed out in connection with the following detailed descriptions of the pres- 100

ent preferred embodiment of the invention, and it will be understood that the foregoing general description and the following detailed description are both exemplary and 5 explanatory, but not restricted of the invention.

Referring now in detail to the present preferred embodiment of the invention as 10 illustrated by way of example in the accompanying drawings, the member which carries the sheet, or usually the group of sheets preparatory to folding, and from which the sheet or group of sheets is folded off, 15 comprises a folding cylinder 1, the shaft 2 of which is journalled in bearings 3 at either end thereof, respectively, upon the side frames 4 of the machine. Suitable means are provided for holding the sheet or group of sheets upon the cylinder, which means may 20 be of any suitable kind or form, but are preferably the usual form of impaling pins (not shown) which engage with the lead end of the sheet or group of sheets. The folding cylinder is also provided with two folding 25 blades, spaced a semi-circumference apart, and preferably medianly of the impaling pins. A cutting cylinder 6 shown conventionally, journalled in bearings 7 on the machine frame, forming no part of the present 30 invention, may be used to cut the sheets from the associated webs at this point, if desired.

Rotatably mounted upon the cylinder 1 are two folding or tucking blades 10 and 11, one being shown at rest and the other performing 35 the folding operation, in Figure 1 of the drawing. As embodied, the folding blades are double-edged and make a half-revolution relatively to the rotating folding cylinder for each fold. A shaft 12 is journalled in 40 bearings near either end thereof, these bearings being mounted in the folding cylinder 1. Fixed to the shaft 12 is a blade-carrying body 14, extending in both directions diametrically from the shaft, and each of these parts is 45 adapted to carry a folding blade.

The blade actuating means is not shown in the present drawings, and it may be and 50 preferably is of the well known Husby cam type, shown exemplarily in the patent to Husby, No. 871,038 of 1907, in which an actuating cam is rotatably mounted beneath the folding cylinder and is provided with a plurality of cam slots formed therein. A head or double arm 20 is fixed centrally of 55 its length to shaft 12, and has at either end thereof outwardly projecting pins or rollers 21 and 22, adapted to cooperate with the actuating cam below the cylinder, to cause the folding blade to be projected from the cylinder to fold the sheet or group of sheets off the cylinder and tuck them between the folding rollers.

Referring now to the embodied form of 60 folding means, in accordance with one feature of the invention, mechanism is provided

for efficiently folding newspapers or other products varying relatively greatly in size, that is, in the number of sheets presented to the folder for folding. For example, a particular newspaper may vary in different editions or issues from four pages to sixty-four pages although the differences are usually 70 relatively not so great.

In accordance with the present invention, and as shown in the illustrative embodiment, 75 there are provided a pair of closely adjacent folding rollers 25 and 26 rotatably journalled directly beneath the folding cylinder 1 and in parallelism with each other and the folding cylinder. Folding rollers 25 and 26 80 are mounted on shafts 27 and 28 respectively and the ends of these shafts are rotatably journalled in bearings 29 and 30, 31 and 32, respectively, as will be more fully described 85 below.

Driving means are provided for positively 90 rotating the folding rollers at a peripheral speed equal to or very slightly in excess of that of the folding cylinder, to take the sheet or group of sheets by the fold and complete 95 the fold. These means preferably comprise 100 gearing connecting the folding rollers with the folding cylinder, to drive the folding rollers from the folding cylinder, and as embodied, a gear 35 is fixedly mounted on shaft 105 2 by which folding cylinder 1 is rotatably journalled in the frame, gear 35 preferably being mounted externally of the frame. Meshing with gear 35 is an idler 36, rotatably 110 journalled externally of the frame by means of a stub shaft, and this idler in turn meshes with the folding roller driving gear 37, rotatably journalled in the press frame by means of a shaft, which carries gear 38 at its 115 inner end, gear 38 being immovable with respect to gear 37. Gear 38 meshes with pinion 39 secured to one end of the folding roller shaft 28 and also meshes with a relatively wide idler pinion 40 rotatably mounted by 120 shaft 41 journalled in a suitable bearing at the side of and fixed with respect to the bearing 32 in which the corresponding end of folding roller shaft 27 is journalled. Idler pinion 40, in turn, meshes with and drives the folding roller pinion 42 at the end of folding roller shaft 27. Pinions 39 and 42 are 125 preferably staggered with respect to each other thereby permitting the folding rollers to be moved close together at the same time maintaining their driving connection with the 130 folding cylinder.

Referring now to the mounting of the folding rollers whereby they may be moved away 135 from each other, the folding cylinder and the folding blade, folding roller 25 is rotatably journalled by means of the ends of folding roller shaft 27 in bearings 29 and 30. Attached to bearings 29 and 30 and supporting the bearings in the desired position are square rods 46, slidable in suitable guides 140 47

at either side of the press frame, guides 47 being attached to the inner sides of the press frame by means of brackets 48. Guides 47 are preferably formed with a removable top 5 plate 49, held in position and against the square rod by means of screws 50, thereby facilitating the removal of the folding roller 25 and its bearings.

The folding rollers are preferably mounted 10 beneath the folding cylinder and are preferably movable to and from each other and toward and away from the folding cylinder and the line of strike of the folding or tucker blade. As embodied, the path of movement 15 of one folding roller is preferably at right angles to the path of movement of the other roller, and both of the folding rollers are movable in a generally downward direction as they are moved away from each other. 20 This movement of the folding rollers with respect to each other and the folding cylinder insures that the space between the folding rollers will be approximately double the space between the folding rollers and the 25 folding cylinder and that there will be sufficient space between the folding cylinder and the forward folding roller 25 to freely pass the head of the sheet or group of sheets as they are fed around on the surface of the 30 folding cylinder. The greater the separation between the folding rollers, the greater will be the distance between the folding cylinder and the folding rollers, and only a single adjustment of the various parts need be made 35 for any desired size of product.

The other folding roller 26 is preferably mounted so as to be resiliently urged towards the forward folding roller 25 to give the proper pinch to the folded sheet or sheets, 40 and is also movable toward and away from the other folding roller and the folding cylinder 1. Folding roller shaft 28 is rotatably journalled at its ends in bearings 31 and 32 formed at the ends of rods 52 which extend 45 away from the folding rollers and are slidably supported in sockets 53 which are formed at the upper ends of the square rods 55, which in turn are slidably mounted in the slideways 56 supported on the inner sides of 50 the press frame by means of brackets 48. The square rods 55 are retained within the slideways by means of the cover plates 57 secured to the upper side of the slideways 56 by means of screws 58. Bearings 31 and 32, 55 and consequently folding roller 26, are resiliently pressed towards folding roller 25 by means of heavy coiled springs 59, retained within sockets 53, and compressed between the ends 60 of the sockets and the large portion 60 of rods 52, while the spring is coiled around the reduced portion 61 of rods 52. The resilient movement of folding roller 26 toward folding roller 25 is preferably limited by means of nuts 62, threadedly secured to a 65 correspondingly threaded portion of the re-

duced end of the rods 52, and bearing against the outer end surface of the sockets 53. The normal position of the folding roller 26 with respect to the folding blades and folding roller 25 can thus be adjusted by turning 70 nuts 62.

For positively moving the folding rollers towards and from each other and the folding cylinder and for holding the folding rollers in any of their adjusted positions, square rods 46 and 55, on which the folding rollers are supported below folding cylinder 1, are each provided at their lower ends with a threaded portion 65 cooperating with a similarly threaded worm gear 66 rotatably mounted on the reduced threaded portion of these rods, and held against axial movement between the faces of a slot formed by the lower ends of the guideways 47 or 56 and lugs 70 secured to the brackets 48. As the worm gears 66 are rotated, the square rods 46 and 52 are correspondingly moved to raise or lower the folding rollers and variably position them relative to each other and to the folding cylinder. 90

Means are preferably provided for simultaneously moving the folding rollers and for always maintaining the folding rollers in parallelism with each other and with the folding cylinder, and means are preferably provided for simultaneously moving all the worm gears 66 to an equal extent. As embodied, meshing with each of the worm gears 66 connected with each folding roller is a worm 67, the worms for moving folding roller 25 being mounted on and secured to shaft 68, while those for folding roller 26 are fixed on shaft 69. Shafts 68 and 69 extend transversely of the frame, and are rotatably journalled in the side frames 4, as well as in alined journals formed in lugs 70 at the sides of brackets 48. At one side of the frame, shafts 68 and 69 carry bevel gears 72, meshing with correspondingly bevelled gears 73 fixed to a shaft 74, rotatably journalled in brackets 75 on the outside of the press frame 4 and extending between the bevel gears 72. At one end, shaft 69 is provided with a hand wheel 76, and any turning of this hand wheel causes a corresponding rotation of all the worm gears 66 together with a similar variation in the position of the folding rollers 25 and 26 with respect to each other and the folding cylinder. 110

The invention in its broader aspects is not limited to the specific mechanisms shown and described but departures may be made therefrom within the scope of the accompanying claims without departing from the principles of the invention and without sacrificing its chief advantages. 120

What I claim is:—

1. A folding mechanism for use with printing presses including in combination a folding cylinder having a tucker blade, a pair of 130

1. folding rollers between which sheets are folded by the tucker blade, and means for moving each of said folding rollers toward and away from each other and the folding cylinder at substantially equal rates. 70
2. A folding mechanism for use with printing presses including in combination a folding cylinder having a tucker blade, a pair of folding rollers between which sheets are folded by the tucker blade, and means for simultaneously moving both folding rollers equal distances toward and away from the folding cylinder, and the line of strike of the folding blade. 75
3. A folding mechanism for use with printing presses including in combination, means for moving the sheets to be folded, a folding blade, a pair of folding rollers between which the sheets are folded by the folding blade, and means for simultaneously moving both folding rollers away from each other and the path of movement of the sheets. 80
4. A folding mechanism including in combination a pair of folding rollers, a folding blade for folding sheets between the rollers as the sheets are fed over the rollers, and means for moving each of said rollers substantially equal distances to and from the line of fold and the path of feed of the sheets. 85
5. A folding mechanism including in combination a pair of folding rollers, a folding blade for folding sheets between the rollers as the sheets are fed over the rollers, means for resiliently mounting one of said rollers permitting it to move away from the other roller, and means for moving each of said rollers substantially equal distances toward and away from the line of fold and the path of feed of the sheets. 90
6. A folding mechanism including in combination a pair of folding rollers, a folding blade for folding sheets between the rollers as the sheets are fed over the rollers, means for resiliently mounting one of said rollers permitting it to move away from the other roller, means for moving each of said rollers substantially equal distances toward and away from the line of fold and the path of feed of the sheets, and gearing for driving said rollers in any of their adjusted positions. 100
7. A folding mechanism for printing presses including in combination a folding cylinder having a tucker blade, a pair of folding rollers between which sheets are folded by the tucker blade, a resilient mounting for one of the folding rollers permitting it to move in a horizontal plane toward and away from the other folding roller and means for simultaneously moving both folding rollers equal distances downwardly toward and away from the folding cylinder and the line of strike of the folding blade. 110
8. A folding mechanism for printing presses including in combination a folding cylinder having a tucker blade, a pair of fold- 120
- ing rollers between which sheets are folded by the tucker blade, means for simultaneously moving the folding rollers toward and away from each other and the folding cylinder, and gearing for driving said folding rollers in any of their adjusted positions. 125
9. A folding mechanism for printing presses including in combination a folding cylinder having a tucker blade, a pair of folding rollers between which sheets are folded by the tucker blade, means for simultaneously moving the folding rollers equal distances toward and away from the folding cylinder and the line of strike of the folding blade, and gearing for driving said folding rollers in any of their adjusted positions. 130
10. A folding mechanism for printing presses including in combination a folding cylinder having a tucker blade, a pair of folding rollers between which sheets are folded by the tucker blade, means for variably positioning said folding rollers relatively to each other and the folding cylinder, a gear driven by the folding cylinder, pinions movable with the folding rollers and driving the folding rollers from the gear in any of the several folding positions of the folding rollers, the several positions of the pinions and folding rollers being such that the pinions are moved substantially tangentially to the gear. 135
11. A folding mechanism for printing presses including in combination a folding cylinder having a tucker blade, a pair of folding rollers between which sheets are folded by the tucker blade, a gear driven by the folding cylinder, pinions driving the folding rollers from the gear, and means for variably positioning said folding rollers and pinions relatively to each other and the folding cylinder, the several positions of said pinions lying along tangents to said gear so that the folding rollers can be driven in any of their folding positions. 140
12. A folding mechanism for use with printing presses including in combination, a folding cylinder having a tucker blade, a pair of folding rollers between which sheets are folded by the tucker blade, means for resiliently pressing one of said rollers towards the other and additional means for spacing said rollers from each other and the folding cylinder while maintaining the rollers equidistant from the line of fold. 145
13. A folding mechanism for use with printing presses including in combination, a folding cylinder having a tucker blade, a pair of folding rollers between which sheets are folded by the tucker blade, means for simultaneously and variably spacing said rollers relative to each other and the line of fold while maintaining the line of fold centrally of the folding rollers, and other means for resiliently mounting one of said rollers allowing it to move away from the other. 150
14. A folding mechanism for use with

printing presses including in combination a folding cylinder having a tucker blade, a pair of folding rollers between which sheets are folded by the tucker blade, means for simultaneously and variably spacing said rollers relative to each other and the line of fold while maintaining the line of fold centrally of the folding rollers, means for resiliently mounting one only of said rollers allowing it to move away from the other and gearing for driving said rollers in any of their adjusted positions.

15. A folding mechanism for printing presses including in combination a folding cylinder having a tucker blade, a pair of folding rollers between which sheets are folded by the tucker blade, a gear driven by the folding cylinder, pinions driving the folding rollers from the gear, and means for simultaneously moving said folding rollers and pinions equal distances from each other and the folding cylinder the paths of movement of said pinions being tangential to said gear whereby the folding rollers can be driven in any of their folding positions.

25. A folding mechanism for use with printing presses including in combination, a folding cylinder having a tucker blade, a pair of folding rollers between which sheets are folded by the tucker blade means for simultaneously and variably spacing the rollers relative to each other and the line of fold while maintaining the line of fold centrally of the folding rollers and for spacing the 30 rollers an equal distance from the folding cylinder means for resiliently pressing one of said rollers towards the other and allowing it to move away from the other roller and gearing for driving the folding rollers from 35 the folding cylinder in any of their adjusted 40 folding positions.

In testimony whereof, I have signed my name to this specification.

WILLIAM E. BECKER.
